UNITED STATES PATENT OFFICE

126,048

DESIGN FOR A TYPEWRITER BRUSH OR THE LIKE

William Anton Lang, Springfield, Mass., assignor to Pro-phy-lac-tic Brush Company, Northampton, Mass., a corporation of Delaware

Application December 6, 1940, Serial No. 97,119

Term of patent 7 years

To all whom it may concern:

Be it known that I, William Anton Lang, a citizen of the United States, residing at 99 School Street, Springfield, in the county of Hampden and Commonwealth of Massachusetts, have invented a new, original, and ornamental Design for Typewriter Brush or the like, of which the following is a specification, reference being had to the accompanying drawing constituting a part thereof.

on the line 4—4 of Figure 1; and

on the line 5—5 of Figure 1.

What is claimed is:

The ornamental design for a typewriter brush
or the like, substantially as shown.

WILLIAM ANTON LANG.
